LADDER SUPPORT

Wilbert P. E. Smith, Thomaston, Conn.

Application October 18, 1946, Serial No. 704,107

1 Claim. (Cl. 228—64)

1

This instant invention pertains to ladders and its main object is to provide a ladder with an attachment to prevent the former from tipping backward or slipping.

Another object of the invention is to provide means preferably associated with the top end of the ladder and preventing slipping, such means being also adapted for supporting a stage or scaffold board at various heights and therefore adapting the ladder for being used as a scaffold.

With these and other objects in view as will become apparent as the invention is understood, the same resides in the novelty of combination, construction and arrangement of parts specifically hereinafter described and claimed in the appended claim.

For a better understanding of the description the same refers to the accompanying drawings illustrating a preferred embodiment of the invention and wherein:

Figure 1 is a side view of my ladder.

Figure 2 is a front elevation thereof.

Figure 3 is an enlarged detail view of the inner side of anti-slipping means.

Figure 4 is an enlarged detail view of the base member.

In the drawings wherein like characters of reference designate like or similar parts throughout the several views, numeral 5 denotes either of a pair of parallel base bars which carry on their outer or remote sides spurs 7 extending slightly below the bottom edges of the bars and engaging the ground to prevent sliding thereon. The front ends of the base bars are held in spaced relation by a rod 9.

To the outer side of either base bar and adjacent the rear end thereof is secured by fasteners 11 a triangular plate 12 to the upper apex of which is pivoted by bolt 13 the lower end of the ladder stile 15 connected by horizontally disposed spaced rungs 17 to the other stile.

The ends of the second rung from the bottom project somewhat beyond the outer sides of the stiles and function as pivots for the upper ends of a pair of diagonal brace bars 20 the intermediate portions 21 of which are offset outwardly (Figures 1 and 2). The lower ends of the bars 20 are connected by a rod 23. Abutment plates 25 are each affixed with their lower portion by fasteners 26 to the inner side of a base bar and include an upper portion extending above the latter. This upper portion is formed into a plurality of spaced hooks 27 opening rearwardly. Each hook is transversely aligned with a hook formed on the abutment plate of the other base bar. Each pair

2 of aligned hooks may receive rod 23 through entrance openings each adjacent the free end of the hook.

To the upper portion of each plate 25 are pivoted by pins 29 the rearward or lower ends of a plurality of latches 30, one for each hook, the free or forward end of each latch terminating in a reduced finger 31 extending at right angles to a shoulder 32 at the upper end of the shoulder. The latch may be swung downwardly to a position in which its finger overlies on top of the rod 23 disposed in one of the hooks 27 with the shoulder engaging the rear side of the rod. The rod may be removed from an aligned pair of hooks or inserted therein only when the latches extend upwardly (Figure 3).

Each stile of the ladder is provided with a series of holes 35 each horizontally aligned with a hole in the other stile. The top pair of aligned holes 20 in Figure 1 is above the top rung and occupied by a rod 36 also passing through the inner ends of the bracket legs 38 the rear ends of which are connected by a board 40 covered on its outer or rear side with rubber 41 preventing slipping on 25 a supporting wall. The legs are on the inner sides of the stiles and carry affixed to their confronting sides ratchet wheels 43 held in a predetermined angular position by pawls 45 pivoted to the inner sides of the stiles. Supports 47 are 30 affixed to the rear edges of the stiles and in proximity to a pair of holes 35 and hold the bracket legs pivoted on the rod 36 inserted in that pair of holes in horizontal position. Figure 1 shows the legs 38 and board 40, 41 in full and 35 dotted lines at different elevations. If a pair of ladder structures is used, a stage or scaffold board 50 may be placed on the pairs of legs, one pair of which is shown in dotted lines in Figure 1. Thus it is apparent that the brackets 38, 40, 41 and board 50 make it possible to use a pair of ladders as a scaffold.

The foregoing description is believed to sufficiently point out the operation of the device.

I desire it to be understood that the described and illustrated embodiment of my invention is merely an illustration or example, not a limitation thereof and that changes and modifications may be resorted to without departing from the spirit of the invention.

What I claim is as follows:

In a ladder, a pair of laterally spaced vertical stiles, rungs extending between the stiles, a pair of laterally spaced horizontal base bars having forward and rearward ends, said stiles having 55 their lower ends pivotally supported on the rear-

ward ends of the base bars, forwardly declining diagonal brace bars having upper ends pivoted on the stiles and lower ends, a horizontal transverse rod extending between and fixed on the lower ends of the brace bars and overlying the horizontal base bars, longitudinally spaced hooks fixed on and rising from the base bars, said hooks facing rearwardly and having rearwardly opening apertures in which said transverse rod is selectively engageable to support said stiles in selected angular relation to said base bars, and latches having one end thereof pivoted on the hooks and free ends, said latches being arranged to occupy forwardly reclining closed positions in which the latches bridge the space between two adjacent hooks, the free ends of the latches having fingers arranged to overlie the transverse rod positioned therein and shoulders beneath the fingers engageable with the side of the transverse rod opposite to that engaged in a hook aperture whereby the transverse rod is held in place, the latches being swingable upwardly from their closed positions to open vertical positions in which the fingers and shoulders are disengaged from the transverse rod to permit the transverse rod to be removed from a hook aperture.

WILBERT P. E. SMITH.
